UNITED STATES PATENT OFFICE.

DE WILTON R. FRENCH, OF WESTPORT, WASHINGTON.

STEAM-EXCAVATOR.

SPECIFICATION forming part of Letters Patent No. 655,218, dated August 7, 1900.

Application filed December 14, 1899. Serial No. 740,321. (No model.)

To all whom it may concern:

Be it known that I, DE WILTON R. FRENCH, a citizen of the United States, residing at Westport, in the county of Chehalis and State of Washington, have invented certain new and useful Improvements in Steam-Excavators; and I do declare the following to be a full, clear, and exact description of the invention, such as will enable others skilled in the art to which it appertains to make and use the same.

The invention relates to steam-excavators.

The object of the invention is to provide a device of this character which shall be simple of construction, durable in use, and comparatively inexpensive of production, and one which shall be efficient in its operations.

To this end the invention consists in certain features of construction and combination of parts, which will be hereinafter fully described and claimed.

In the accompanying drawings, Figure 1 is a perspective view of my improved dredge. Fig. 2 is a longitudinal sectional view illustrating the position of parts as the dredge is being drawn forward in the act of sweeping up dirt. Fig. 3 is a similar view illustrating the position of parts at the instant the dredge has reached the end of its forward travel and is in the act of being drawn back to its point of starting. Fig. 4 is a top plan view. Fig. 5 is a detail perspective view of a portion of one of the plow-actuating levers and its rack-bar.

In the drawings the same reference characters indicate the same parts of the invention.

1 denotes the body of the dredge, consisting of the parallel side pieces 2 and the curved end piece 3, the upper end of which terminates in a hood 4, and the lower end of which has secured to it a removable shear 5.

6 denotes diagonal braces bolted to the side pieces of the dredge and having their upper ends joined together and projecting above the upper edges of the side pieces.

7 denotes a discharger, the lever-arms 8 of which project upwardly and are journaled upon a rod or shaft 9, bolted to the upper ends of the diagonal braces. The extreme upper ends of these arms are bolted together and

are provided with shackles 10 and 11, the former to receive the forward haul-line 12 and the latter the return haul-line 13.

14 denotes side bars bolted to the sides of the dredge-body. The rear ends of these bars are bent at right angles, as shown at 15, and thence parallel, as shown at 16, where they are bolted together. A supporting-roller 16^a is journaled between said side bars immediately at the rear of the dredge-body. Steps or supports 17 are bolted to the parallel portions 16 for the attendant or operator to stand upon. 18 denotes arms secured to the forward ends of these bars and having their forward ends converging and bolted to a draw-bar 19, to which the forward haul-line 20 is attached. This haul-line and the haul-line 12 are connected to the forward haul-cable 21, while the return haul-line 22 is attached to the eye of the draw-bar 23, bolted between the parallel portions 16 of the side bars. The rear end of this line 22 and the line 13 are connected to the return haul-cable 24.

25 denotes a gang of plows pivoted upon a rod 26, bolted to the pivoted arms 18. These plows work in advance of the shear and cut into the earth, so that as the shear comes along it will have no difficulty in making a transverse cut and scooping dirt up into the body 80 of the dredge. To adjust the depth of the cut made by the plows, I provide levers 27, the forward ends of which are pivoted in bearings 28, swiveled to an arched bar 29, bolted to the forward end of the dredge-body. The 85 forward ends of the levers are formed with hooks 30, which engage chains 31, connected to the plows. The rear ends of these levers are provided with fixed dogs 32, which are adapted to engage vertical racks 33 and be 90 guided in their movement by rods 34. The racks 33, if desired, may be connected at their upper ends by a cross-piece 35, and the inner sides of the levers may be provided with springs 36, adapted to have a sliding engagement with the guide-rods 34 and exert their energy to force the levers laterally to hold the fixed dogs in engagement with the rack-bars. This lateral movement of the levers is permitted by reason of pivoting them to the swiveled bearings 28, hereinbefore referred to.

The operation of the machine is as follows:

Assuming the dredge to be drawn forward in the direction of the arrow indicated in Fig. 2, the lines 12 and 20 are taut. The line 12 being connected to the lever-arms of the dis-
5 charger draws said lever-arms forward and holds said discharger back against the rear end of the dredge and permits the dirt which is loosened by the plows and scraped up by the shear to lodge within the body of the dredge. After the dredge has reached the end of the line or the point at which it is de-
10 sired to discharge its load the cable 21 is re- leased and the cable 24 is now drawn rear- ward, which through its connection 13 with the lever-arms of the discharger draws the lever - arms rearward and swings the dis-
15 charger forward, which will force the dirt from out of the dredge. After the dredge has been returned to its starting-point power
20 is again applied to the cable 21 and the dredge is again drawn forward, as above described, and this operation is repeated until the de- sired amount of dirt has been removed.

The machine is designed for grading, dredg-
25 ing, and handling earth, gravel, and loose rock and is hauled back and forth by two donkey-engines, one arranged at each end of the line.

From the foregoing description, taken in
30 connection with the accompanying drawings, the construction, operation, and advantages of my improved excavator will be readily ap- parent without requiring an extended expla- nation.

35 It will be seen that the device is simple, that its construction permits of its manufac- ture at small cost, and that it is exceedingly well adapted for the purpose for which it is designed, and it will of course be understood
40 that various changes in the form, proportion, and the minor details of construction may be resorted to without departing from the prin- ciple or sacrificing any of the advantages of this invention.

45 Having thus described the invention, what

is claimed, and desired to be secured by Let- ters Patent, is—

1. The combination with the dredge-body provided with a shear; of a gang of plows pivotally connected with the dredge-body in 50 advance of the shear, and a discharger piv- oted within said body, substantially as and for the purpose set forth.

2. The combination with the dredge-body provided with a shear; of a gang of plows 55 pivotally connected to the dredge-body in advance of the shear, a pivoted lever, a connection between one end of the lever and the plows, and a rack-bar for engaging the opposite end of the lever for holding it in adjustment, substan- 60 tially as and for the purpose set forth.

3. The combination with the dredge-body provided with a shear; of a discharger piv- oted within said body and provided with le- 65 ver-arms, forward haul-lines, the rear end of one connected to the lever-arms of the dis- charger, and the rear end of the other con- nected to the dredge-body, the forward ends of said lines being connected to a forward haul-cable, whereby when the dredge is drawn 70 forward, the discharger will be held in the rear portion of the dredge, and return haul- lines, the forward end of one being connected to the lever-arms aforesaid, and the forward end of the other connected to the dredge- 75 body, the rear ends of said lines being con- nected to a return haul-cable, whereby when strain is released from the forward haul-ca- ble and strain exerted upon the rearward haul-cable, the discharger will be operated to 80 discharge the dirt from the dredge and the dredge be returned to its point of starting, substantially as and for the purpose set forth.

In testimony whereof I have hereunto set my hand in presence of two subscribing wit- 85 nesses.

DE WILTON R. FRENCH.
